UNITED STATES PATENT OFFICE.

WILLIAM H. ELLIOT, OF NEW YORK, N. Y.

MAGAZINE FIRE-ARM.

SPECIFICATION forming part of Letters Patent No. 239,748, dated April 5, 1881.

Application filed October 23, 1880. (No model.)

To all whom it may concern:

Be it known that I, WM. H. ELLIOT, of the city and State of New York, have invented a new and Improved Magazine Fire-Arm, of which the following is a specification.

The object of my invention is to provide a more convenient, simpler, and more practical magazine fire-arm than any now in use; and the nature of my invention consists in the use of certain appliances and methods, which are fully set forth in the following specification and claims.

Figure 1 is a vertical longitudinal section of the arm, showing the lock and breech block or bolt in elevation. Fig. 2 is a bottom view of the rear end of the magazine-tube. Fig. 3 is a vertical section of the same. Fig. 4 is an elevation of the principal parts of the breech mechanism. Figs. 5, 6, 7, 8, and 9 are elevations of the forward end of the bolt and toggle-joint, showing several modifications of the same. Fig. 10 is a plan of the sliding stop-pawl, showing its relation to the receiver and magazine. Fig. 11 represents the opening through the side of the receiver and sections of the button which controls the feed or stop pawl. Fig. 12 is a bottom view of the button. Fig. 13 is a side elevation of the same. Fig. 14 is an elevation of a portion of the lock. Fig. 15 is a plan of the lever, toggle-joint, and carrier. Figs. 16 and 17 represent modifications of the same.

a is the receiver; *a'*, the barrel; *a''*, chamber of the barrel with a cartridge in it; *b*, magazine-tube; *b'*, follower; *b''*, magazine-spring; *b'''*, offset in the rear end of the magazine-tube, having in it a cartridge-head, *a'''*; *c*, breech block or bolt; *c'*, pendent projection of the same; *c''*, joint between the same and the forward link of the toggle-joint; *c'''*, recess in the upper side of the links of the toggle-joint; *d*, hammer; *d'*, pivot of the same; *d''*, main-spring and stirrup; *e*, carrier, swinging upon pivot *g'''*; *e'*, ratchet-projection on the carrier; *e''*, pawl which acts upon the ratchet *e'*, being pivoted to the rear or connecting link of the toggle-joint at *i*; *e'''*, bar through which the projection *e'* trips the pawl *e''*; *g*, guard-lever; *g'*, rear or connecting link of the toggle-joint which connects the lever with the receiver; *g''*, joint between the two links of the toggle-

joint; *g'''*, pivot which joins the rear end of connecting-link *g'* to the receiver; *i'*, mortise through the rear portion of the guard-lever for the trigger; *i''*, rear surface of the same; *k*, charge-opening of the magazine; *k'*, cover of the same; *k''*, wide part of the opening; *m*, sliding feed-pawl; *m'*, button which controls the same; *m''*, screw which fastens the button to the pawl *m*; *m'''*, angular projections into the opening *n* in the side of the receiver; *n'*, section of button *m'*; *n''*, the same in the forward position; *n'''*, the same in the rear position; *o*, *o'*, *o''*, and *o'''*, positions of the thumb and fingers while manipulating the arm; *r*, *r'*, cover of the receiving-chamber; *r''*, carrier-spring; *r'''*, spring of pawl *e''*; *r''''*, shoulder formed by the offset *b'''*; *s*, trigger; *s'*, projection from the lower end of the same; *s''*, opening in the guard for projection *s'*; *s''''*, pivot of the trigger *s*; *t*, tang-strap; *t'*, trigger-spring; *t''*, offset in the carrier; *t''''*, braces; *u*, friction-catch; *u'*, spring of the same.

The invention herein described refers to that kind of magazine-arm in which the breech-block has a reciprocal movement in a line with the barrel for opening and closing the chamber, and in which said movement is given to the breech-block by means of a single toggle-joint, which has its forward link extended rearward under the arm to form a lever, and is an improvement upon the arms patented to me May 13, 1862, and September 14, 1880, to which patents special reference is made.

The arm in its closed position is shown in Fig. 1, and in Fig. 4 the principal devices of the breech mechanism are shown in their relative position when the arm is open.

For a magazine I employ a single tube provided with the usual cartridge-propelling devices, and located under the barrel.

To charge the magazine, open the cover *k'* and move the feed-pawl forward by means of the button *m'*, which projects through the side of the receiver, as seen in Figs. 10 and 11. Then give the button a quarter-turn, which locks the pawl in its forward position. By this means the follower or cartridges, if there be any in the magazine, are moved far enough forward to admit the insertion of the ball end of a cartridge through the opening *k* and behind the head of the rear cartridge in the

magazine. The cartridge is then pushed forward and its head dropped down in front of the feed-pawl, as shown in Fig. 10. This operation may be repeated till the magazine is full. If the magazine be not required for immediate use, the feed-pawl has to be left locked in its forward position by the button, as seen at n'' , Fig. 11. If it be required for immediate use, the feed-pawl has to be released from its forward position, which is done by turning the button to the position indicated at n' , when, by the power of the magazine-spring, it will be forced back to the rear, where it may be locked as it was in the forward position by giving the button a quarter-turn, as set forth in the last above-mentioned patent.

By reference to Fig. 3 it may be seen that there is an offset in the magazine-tube equal in extent to the projection of the head of the cartridge over the body of the same. Through this offset the body of the cartridge passes in a right line; but the head of the cartridge, having a diameter nearly equal to the bore of the magazine-tube, first comes against the unyielding shoulder r''' , then makes a slight lateral movement into the offset portion of the tube, when it continues its forward movement and is delivered upon the carrier. The shoulder r''' is not cut at right angles to the tube, but is beveled, so that when the head of the cartridge strikes it, it glides into the offset portion of the tube without stopping its forward movement. When the last cartridge has been expelled from the magazine the follower has its forward movement arrested by the stop or shoulder r''' , and, as it has a long bearing upon the inner surface of the magazine-tube, it cannot pass laterally into the offset. By the employment of this offset for stopping the follower I am able to use a magazine-tube of reduced size, as the follower, as a means of stopping it, is not required to be larger in diameter than the cartridge-head. The operation of the offset upon the follower and cartridge-head is the same whether the cartridge be presented to it ball first or head first.

By reference to Fig. 2 it may be seen that the charge-opening k is only wide enough at the point k'' to allow the head of the cartridge to pass into the magazine-tube, while the forward part of said opening only admits the body of the cartridge. As the cartridge is being inserted the head slides along upon the edges of the opening till it reaches the point k'' , when it drops into the tube just forward of the feed-pawl, when that device is locked in its forward position. The follower having a cylindrical form to fit the bore of the tube, and being considerably more than half surrounded by the tube at all points of the charge-opening except at the point k'' , it cannot by any means be got out of the magazine through the charge-opening, while at the same time the charge-opening will admit freely a cartridge having a head of equal diameter with the follower. By the employment of this form of charge-opening in connection with the offset

b'' , I am enabled to use a follower of equal diameter with the cartridge-head, and consequently a smaller and a more compact magazine. 70

The opening n through the side of the receiver is just wide enough for the flattened neck of the button to slide back and forth in; but it has a circular enlargement at each end 75 to allow the button to be rotated a quarter-turn for the purpose of locking the feed-pawl. To prevent the button from being carelessly turned too far I employ the angular projections m''' in each circular enlargement, as shown 80 in Fig. 11. In manipulating the feed-pawl the neck of the button readily passes from the narrow part of the opening into the circular enlargements, as seen at n''' , where it may be turned till it comes in contact with the angular projections or stops, as seen at n'' . These angular projections m''' are a portion of the material of the receiver not cut away in forming the enlargement at each end of the opening. Thus it may be seen that the rotating 90 and sliding button m' , by means of its flattened neck, is securely locked at each end of its sliding movement, and, in connection with the projections m''' , is stopped in its rotary movement. To reserve the magazine it is only necessary to lock the feed-pawl in its forward position, when it is out of the reach of that portion of the guard-lever which actuates it when locked in the rear position, as seen in Fig. 10. 95

By reference to Figs. 1, 4, and 14 it may be seen that the trigger is pivoted to the tang-strap, and that the guard-lever has a mortise, i' , through it, over the rear portion of the guard, so arranged that when the guard-lever is closed up against the receiver the trigger passes into 100 said mortise and assumes a proper position in relation to the guard. Opening the arm brings the hammer to full-cock, and while in that position, the point of the trigger being in the full-cock notch, the act of closing the arm 105 causes the projection s' on the lower end of the trigger to slide down upon the surface i'' of said mortise, and thus prevent the lock from being pulled off by accident at any time after the trigger enters the mortise and before the 110 guard-lever is brought fully to its place against the tang-strap. After the lever has been brought home a pull upon the trigger to fire the arm causes the projection s' on the trigger to enter the recess s'' in the guard, and thus 115 to act as a hook to hold the guard-lever in place at the moment the arm is fired. In this way the accident of blowing the guard-lever down by an unusual escape of gas, or of firing the arm by accident before the parts are in a 120 proper position to resist the recoil, is provided for. The full-cock notch must be enough higher than the safety-notch to leave room for the trigger to be pulled out of the safety-notch at any time, while yet the action of projection s' 125 upon the surface i'' will prevent the lock from being cocked or the arm fired before the parts are in a safe position. 130

By reference to Figs. 1, 4, and 16 it may be

seen that the carrier e and the connecting-link g' are both joined to the receiver by the pivot g''' , and that both links of the toggle-joint are recessed on the upper side to make room for the carrier. This recess, with the carrier in it, is shown in Fig. 16. By this method of making room for the carrier it becomes practicable to place that device directly over the toggle-joint, and between it and the breech-block, without increasing the depth of the receiver for that purpose. The carrier is provided with a ratchet-projection, e' , which is acted upon by the pawl e'' , the latter device being pivoted to the connecting-link at i and provided with a spring, r' . In opening the arm, as the link and lever change from the position shown in Fig. 1 to that shown in Fig. 4, the pawl e'' , swinging with the connecting-link, comes in contact with the ratchet-projection e' and depresses the carrier against the spring r' . At the moment the carrier has been depressed sufficiently to receive a cartridge upon its upper surface from the magazine the rear corner of the projection e' comes against the end of the bar e'' . This raises the pawl e'' and liberates the carrier, which is immediately elevated to the position indicated by broken lines, Fig. 4, by the spring r' carrying the cartridge up before the breech-block. The connecting-link is peculiarly adapted to operate the carrier, as its movement is comparatively slow when the pawl e'' first meets the ratchet e' , and gradually becomes slower till the pawl is tripped, so that when the arm is manipulated rapidly the carrier operates without violence and almost noiselessly.

By reference to Figs. 1, 5, and 16 it may be seen that the dependent projection e' is bifurcated, and that the carrier works through the center of it. In Fig. 1 one side of the projection is broken away to show the carrier.

Fig. 6 is a modification of the same general construction of parts that is shown in Fig. 16, except that the projection e' is not bifurcated, but drops down upon one side of the carrier. In this case the links are provided with recesses for the carrier, the same as shown in Fig. 16, the recesses being moved a little to one side, so as to agree in arrangement with the forward end of the carrier. By this construction the carrier does not act directly under the center of the cartridge, but a little at one side, which causes the cartridge to rest lightly against one side of the receiver as it is raised, and prevents it from being thrown upward beyond the limit of the upward movement of the carrier.

Figs. 7, 9, and 17 represent a modification of the same combination of devices. In this case the links are not recessed, the carrier being located at the side of the toggle-joint and having an offset, t'' , the spring r' acting laterally as well as vertically upon the carrier. When the breech-block is drawn back the carrier is thrown to a central position by the spring, where it remains to do its work until

the arm is closed, when the projection e' crowds it to one side, as shown in Fig. 17. In Fig. 9 the joint e'' is reversed, the central portion of the joint being formed upon the forward end of the lever, while the outer portions are formed by dividing or recessing the projection e' .

Figs. 8 and 15 represent two independent carriers, one upon each side of the toggle-joint and dependent projection. These carriers are both operated by a pawl, e'' , which has a point wide enough to reach them both. This pawl is so constructed that one of the carriers is released a little before the other, which has the effect of retarding the upward movement of the cartridge by throwing it laterally against the side of the receiver. These carriers are each provided with a suitable spring, and also with a brace, t''' , to keep them in place. In any case the pawl e'' has to be pivoted to the connecting-link g' directly under the carrier. If the carrier works in a recess in the connecting-link, then the pawl has to be placed in the same recess.

The carrier in any of the modifications represented may be pivoted to the receiver independently of the pivots of the connecting-link, and may be operated by a cam on said link; but the method herein shown for operating the carrier is preferable.

It will be observed that the carrier is depressed and released to rise again during the backward movement of the breech-block, so that the cartridge is sure to be carried to a position before the chamber of the barrel by the carrier and spring before the movement of the breech-block can be reversed.

The letters o , o' , &c., indicate the position of the thumb and fingers while manipulating the arm with the magazine connected. The second finger rests at all times upon the guard at o . In opening and closing the arm the thumb takes the position of o' and the first finger that of o'' , whereby the pressure of the thumb and first finger tends to carry the forward end of the lever backward, as well as to carry the rear end of the lever forward, which makes the manipulation of the parts easier than it would be by the pressure of the thumb alone. In firing the arm with the first finger on the trigger, the thumb takes the position of o''' across the wrist. As the second finger never leaves the point o , the relative positions of the several points to the hand are never lost, which facilitates sure and rapid movements of the hand.

Having described my invention, what I desire to have secured to me by Letters Patent of the United States is—

1. In a magazine fire-arm having a magazine located under the barrel and a feed-pawl controlled by a sliding and rotating button provided with a flattened neck, which works in a slot in the side of the receiver, and in combination therewith, the stops m''' projecting into the enlarged ends of said slot, whereby the feed-pawl is locked at each end of its

sliding movement and the button is stopped in its rotary movements, substantially as and for the purpose specified.

2. In a magazine fire-arm having a magazine located under the barrel and provided with the usual cartridge-propelling devices the offset b''' , constructed, as shown, at the rear end or discharge-opening of said magazine, whereby the cartridge readily passes out of the magazine, while a follower of the same diameter as the head of the cartridge is effectually stopped, substantially as specified.

3. In a magazine fire-arm having a breech-block for opening and closing the chamber which moves in a line with the barrel and is manipulated by means of a toggle-joint, and a guard-lever having the mortise v and recess s'' , and in combination therewith a trigger

pivoted to a fixed point upon the arm and provided with the projection s' , whereby the guard-lever is locked in position at the moment the arm is fired, substantially as and for the purpose specified.

4. In a magazine fire-arm, a breech-block for closing the chamber which moves in a line with the barrel and is manipulated by means of a toggle-joint and lever of the kind described, and in combination therewith a carrier pivoted to the receiver, with the connecting-link at g''' , the pawl e'' pivoted to the link g' and actuated by the projection c' through the bar e'' , substantially as and for the purpose specified.

WM. H. ELLIOT.
